RATCHET FOR COIN CONTROLLED MACHINES

Lionel P. Klopner, Fort Worth, Tex.

Application August 1, 1949, Serial No. 108,001

1. Claim. (Cl. 74—17.5)

1 This invention relates to vending machines, disk token dispensing machines, and the like, and has reference to improvements in actuating mechanisms therefor.

An object of the invention is to provide an improved ratchet construction and combination whereby pilfering from machines of the described class is eliminated or substantially reduced.

Particularly, the invention has to do with a ratchet construction and arrangement for co-action with the segment ratchet gears of machines of the described class now in use, and whereby said gear must complete its movement in either direction before it can again be moved in the same initiated direction.

Machines of the described class usually have the longitudinal centers of the ratchets positioned, by means of tension springs, other than through the pivotal centers of the segment gears, and which arrangement was operative when used with a ratchet having a single angularly disposed detent. However, the conventional single detent ratchet permitted pilfering, as will be shown. It is therefore an object of the present invention to provide a ratchet having double detents for making it necessary to complete the movement of the segment gear in either direction, and yet serve the intended purpose although the length of said ratchet is misaligned with respect to the pivotal center of said gear.

Figure 1 is a broken elevation of the actuating mechanism of a machine of the described class, and showing the improved ratchet positioned therein.

Figures 2 and 3 are elevations of the improved ratchet, and illustrate the locking effect so as to make necessary the complete movement of the segment gear in either direction after said gear has been initially actuated.

Figure 4 is an enlarged elevation of the improved ratchet and particularly shows, by means of center lines, the relative lengths of the detents thereon.

A conventional vending or disk token dispensing machine will be described before disclosing the present invention in order that the latter may be readily understood and appreciated. The machine illustrated in Figure 1 includes a base 10 having a frame 11 supported thereon by means of legs 12 and feet 13. An operating lever 14 is pivotally secured relative to the frame 11 at the point A. Within the lever 14 there is a longitudinal groove 15 for engaging opposite sides of a roller 16 mounted on an extending arm 17 of a segment type ratchet gear 18 having teeth 19

along its arcuate edge. A projection 20 on the gear 18 accommodates a finger 21 pivotally supported on said gear by a pin 22. The pin 22 is located near one end of the finger 21, and a tension spring 23 is connected with said finger above said pin and is attached to the projection 20 by means of a screw 24. A central and relatively large opening 25 is formed through the finger 21 and receives a small pin 26 projecting from the segment projection 20. The outer end of the finger 21 is downwardly and outwardly curved, as at 27, for sliding contact with the pointed end 28 of an operated lever 29, the latter being secured at its end opposite the point 28 to a shaft 30 journaled in the frame 11. Another operated lever 31 is also secured to the shaft 30 and extends toward and is received within a slot 32 in a bell crank 33 pivotally mounted on the frame 11 by means of a shaft 34. A roller 35 is mounted on the last described operated lever 31 for action within the bell crank slot 32. The operated levers 29 and 31 are normally moved in a downward direction by means of a tension spring 36 connected between the base 10 and one of the operated levers 29. The end of the bell crank 33 opposite the slot 32 is provided with a pawl 37 which is moved outwardly by a tension spring 38 connected with said bell crank to engage the teeth 39 of an indexing wheel 40 mounted on a shaft 41 supported by the frame 11. The indexing wheel 40 is not shown in detail, be it sufficient to say that this wheel regulates the discharge of merchandise, disk tokens, or the like, in any machine of this type.

35 A ratchet 42 is pivotally mounted on a pin 43 secured to the frame 11 and is arranged for co-action with the teeth 19 of the ratchet segment 18. A tension spring 44, connected with one end of the ratchet and with the frame 11, positions said ratchet substantially perpendicular to the ratchet gear 18 when not acted upon by the teeth 19. The foregoing described machine, with the exception of the particular ratchet 42, 40 to be described in detail, is conventional and has been described for the purpose of better illustrating the new ratchet, be it sufficient to say that the conventional ratchet (not shown) had a single detent and was angularly disposed so as to prevent movement of the ratchet gear 18 in one direction only when engaging the teeth 19.

45 It will be noted in Figure 1 that the length of the ratchet 42, when not engaging the teeth 19, is not aligned with the center of the shaft 45. 50 As will become apparent from the description of

operation, one of the detents 46 is longer than the other detent 47 on the improved ratchet 42 as particularly shown in Figure 4 so as to accommodate the non-alignment of the length of said ratchet with the center of the segment gear supporting shaft 45.

In operation, the lever 14 is moved downwardly about the point A, causing the teeth 19 of the ratchet segment 18 to move in a corresponding direction. During the last referred to movement, the finger 21 is moved upwardly, slidably engaging the point 28 of the operated lever 29, and causing the other operated lever 31 to move upwardly and to move the bell crank 33 about its supporting shaft 34. By reason of the pawl 37, the end of the bell crank supporting the same passes the teeth 39 on the index wheel 40. As the movement of the lever 14 continues, the shorter detent 46 engages the teeth 19 of the segment gear 18 in the manner illustrated in Figure 3, and thus locking the latter against a return movement until the detent 46 is positioned, relatively, beyond the end of said teeth. After the finger 21 raises the lever 29, the curved end of said finger passes beyond and releases the point 28 of said lever, thus allowing the spring 36 to actuate the pawl 37 and spin the indexing wheel 40. The lever 14 is then returned to its original position by means of springs (not shown), and in which event the longer detent 47 engages the teeth 19 in the manner illustrated in Figure 2 and thus prevents the return of the segment gear to its position just prior to the described return movement.

It has been found, in the described machine having the single angularly directed detent (above referred to), that after the index wheel 40 has been set for dispensing merchandise or

tokens, that partial operation of the lever, while said prior detent is riding above the teeth 19, will cause the machine to discharge the merchandise or tokens. By reason of the described improved ratchet, and by reason of the described locking positions, as particularly shown in Figures 2 and 3, such pilfering of merchandise or tokens may be prevented.

The described form of the invention may be made in many ways within the scope of the appended claim.

What is claimed is:

In combination with a vending machine or the like having a segment ratchet gear therein, a ratchet pivotally supported opposite the teeth of said gear, a pair of angularly disposed detents of unequal lengths integral with said ratchet and arranged for engaging the teeth of said gear, and spring means positioning the mean longitudinal center between said detents asymmetrically relative to the pivotal center of said gear.
